UNITED STATES PATENT OFFICE.

GEORGE H. PICKHARD, OF DETROIT, MICHIGAN, ASSIGNOR TO MCCORD RADIATOR & MFG. CO., OF DETROIT, MICHIGAN, A CORPORATION OF MAINE.

ATTACHMENT FOR PUNCH PRESSES.

Application filed March 7, 1925. Serial No. 13,779.

Top tanks for motor vehicle radiators are usually made from sheet metal, such as brass, by a drawing operation, and have substantially flat front and rear walls and a top wall 5 with a centrally disposed opening for the filler neck of the core.

In this type of tank, the casting for the upper water connection is riveted to the rear wall about an inlet opening formed therein, 10 with the base flange of the casting seating in a depression or recess in the rear wall of the tank about this opening. Also there is a shield or baffle plate in the tank extending at an upward inclination from the front wall 15 across the inlet opening to prevent water being forced into the tank by the pump in the cooling system from splashing up into the filler neck and running out of the vent or overflow tube of the core. This shield 20 or baffle plate is riveted at its lower end to the front wall of the tank and the vent or overflow tube passes through the rear wall of the tank at one side of the plate. The form 25 of opening for this tube is covered by Patent No. 1,568,526, granted January 5, 1926, to Charles W. Owston.

The main object of my invention is to provide a punch and die operating mechanism for use as an attachment for a punch press for punching in a single operation all of the rivet holes in the front and rear walls of the tank for the casting and shield plate, respectively, and also the recess for the casting, as well as the opening in the rear wall of the 30 tank for the vent or overflow tube, thus combining in one operation all of the steps which heretofore have required several separate operations.

A further object of my invention is to so 40 construct the punch operating mechanism that the descent of the upper punch will cause the lower punch to move upward and pierce the rivet hole in the front wall of the tank for the shield or baffle plate simultaneously 45 with the piercing of the rear wall of the tank in making the rivet and other holes for the casting and the depression or recess for the base of the same.

Other and further objects of my invention 50 will appear from the following specification, taken in connection with the accompanying drawings, in which—

Figs. 1 and 2 are top and rear views, respectively, of the top tank after being oper-

ated on by a punch and die construction of 55 my invention;

Fig. 3 is an enlarged vertical sectional view on line 3—3 of Fig. 2 with the casting secured in place;

Fig. 4 is a side view of a punch press 60 equipped with a device of my invention;

Fig. 5 is an enlarged horizontal sectional view on line 5—5 of Fig. 4, and looking down on the upper die;

Fig. 6 is a vertical sectional view on line 65 6—6 of Fig. 5 with the punches shown separated from their associated dies;

Fig. 7 is a similar view showing the punches engaged with their respective dies;

Fig. 8 is a vertical sectional view on line 70 8—8 of Fig. 5;

Fig. 9 is a horizontal sectional view through the upper punch on line 9—9 of Fig. 6; and

Figs. 10 and 11 are vertical sectional views 75 on lines 10—10 and 11—11, respectively, of Fig. 9.

The top tank shown in Figs. 1 to 3 is drawn from sheet metal, preferably brass, and has substantially flat front and rear walls 1 and 2. 80 The top wall 3, in the form of tank shown, is curved from the center of the tank toward its ends and has a centrally disposed opening 4 for the filler neck (not shown) of the radiator core.

An elongated horizontal opening 5 is punched in the rear wall 2 midway between the ends of the tank to provide an inlet opening for the casting 6 of the upper water connection. Around the opening 5 there is an 90 outwardly projecting flange to fit inside of the casting 6, as shown in Fig. 3, so that no gasket is required. The base flange of this casting 6 seats in a depression or recess 7 formed in the wall 2 about the flanged opening 5. The casting is secured to the wall 2 in this recess by four rivets 8, 8, preferably at the corners of the casting. The depression or recess 7 is rectangular, as shown in Fig. 2, so as to receive the like shaped base of the 100 casting 6.

In the tank there is a shield or baffle plate 9 extending at an inclination upward from the front wall 1 to the rear wall 2 across the opening 5, as shown in Fig. 3. This plate 9 is secured by a single rivet 10 to the front wall 1 and is of a size or area to extend on opposite sides of the opening 5 (Fig. 2) so as to prevent

the water being forced into the tank by the pump in the system from splashing up in the opening 4 and escaping by the vent or overflow tube 11, which enters the rear wall 2 of the tank at a point offset to one side of the casting 6. The upper end of this tube 11 extends into the filler neck (not shown) through the opening 4, as in radiator design.

The opening 12 in the rear wall 2 for the tube 11 is formed by first slitting the wall 2 along a straight line approximating the outside diameter of the tube and then forcing the metal of the wall on opposite sides of the slit out of the plane of the wall so that the portion of the metal on one side of the slit extends into the tank and the other on the other side of the slit on the outside of the tank, as shown in Fig. 1. These metal portions are curved to fit the curvature of the tube 11 where it enters the tank, as described and claimed in the co-pending application of Charles W. Owston, as aforesaid.

The punch and die mechanism of my invention is shown in Figs. 4 to 8. This mechanism includes an upper punch 13, a lower punch 14, and co-operating dies 15 and 16 between them, as shown in Figs. 6 and 7. The upper punch 13 is carried on the under side of a punch holder 17 on the reciprocating ram or other movable part 18 of the punch press. The punch 13 has four piercing punches 19, 19 co-operating with a like number of holes 20, 20 in the upper die 15 to produce holes for the four rivets 8, 8 which secure the casting 6 to the rear wall of the tank. This upper punch 13 is provided with a centrally disposed piercing member 21 co-operating with a hole 22 in the upper die 15 to produce the elongated opening 5 in the rear wall of the tank. The upper punch 13 is further provided with an impression plate or section 23 surrounding the punch 21 and co-operating with a recess 24 in the upper die 15 to depress the portion of the tank wall 2 around the opening 5 to make a flange about the latter and also the seating recess 7 for the base flange on the casting 6. The hole 22 continues through the die supporting projection 25 of the attachment 26 to discharge the slugs formed in punching the hole 5. As shown in Figs. 7 and 8, the holes 20 also continue through this support for the same purpose.

The lower punch 14 is a piercing punch and co-operates with the lower die 16 to make the hole for the single rivet 10 for fastening the plate 9 to the front wall 1. The lower die 16 has a slug receiving opening 27 leading to the main passage 22. The tank 1 after being blanked with hole 4 in its top wall is placed over the projection 25 so that its rear wall 2 is on top of the upper die 15 and its front wall 1 is on the under side of the lower die 16, as shown in Fig. 7.

A plunger 28 is secured to the upper punch carrier 17 and extends down into a bore or pas-

sage 29 in the body part 26 of the fixture. The lower end of the plunger 28 is cut off at an angle of approximately 45°, as shown. The lower punch 14 is carried by a similar plunger 30, only much shorter than the first one, and has upward and downward sliding movement in a bore 31 in the fixture 26. This bore is parallel with the bore 29 and is also offset outwardly from it, as shown. The lower end of this plunger 30 is also beveled or cut off at 45°. The bores 29 and 31 open at their lower ends into a cross bore 32 in which slides a short plunger 33 cut off at 45° angles at both ends to provide co-operating cam surfaces for those on the adjacent lower ends of the plungers 28 and 30.

The plunger 30 carries a downwardly extending steel rod 34, which extends through an elongated slot 35 in the outer beveled end of the short plunger 33. This slot allows this third plunger to slide back and forth in its bore without hindrance by the rod 34. A coiled spring 36 is about the lower end of the rod and bears against the bed or other fixed part of the punch press and serves to normally draw the plunger 30 downward.

In operation, when the upper punch 13 is moved downward by the action of the press, the first plunger 28 is carried downward and as soon as its beveled lower end strikes the adjacent beveled end of the third plunger 33, the latter is forced forward and acts on the lower end of the second plunger 30 to raise the lower punch 14 and cause it to pierce a single hole in the front wall of the tank, simultaneously with the operation of the upper punch 13 on the tank wall 2.

On return of the upper punch 13 by the press, the plunger 28 is raised and the spring 36 then acts to move the plunger 31 downward and forces the third plunger 33 rearward to be reset for the first plunger 28.

To make the opening 12 for the tube 11, a punch 37 and a die 38, in the form of separate plates, are respectively secured to the carrying parts for the upper and lower punch 13 and die 15, respectively, as shown in Fig. 8. This punch and die construction 37-38 is provided with co-operating projections and recesses to form the tube opening 12, as shown.

The entire structure shown and described is adaptable as an attachment for punch presses, and enables all of the rivet and other holes and the recess heretofore described to be made in a single operation, this greatly facilitating the production of the tanks by avoiding a multiplicity of separate and expensive operations, as heretofore required.

The details of structure shown and described may be variously changed and modified without departing from the spirit and scope of my invention.

The upper punch 13 has upper and lower plates 13^a, 13^b connected together adjacent

their four corners by screws 13^c about which are coiled springs 13^d, as indicated in Figs. 9 and 11. When the stroke of the press is up, the punches 19 and 21 are flush or even with the impression plate 23, as shown in Fig. 6. On the down stroke, the plate 23 is brought against the tank wall 2 and holds the tank on the die. A continued downward movement of the press forces the center punch 21 through the wall to make the elongated hole 5. The impression plate 23 follows into the recess 24 in the die 15 to make the depression for the base flange of the casting 6. When the bottom of the recess 24 is reached, a continued downward movement of the press overcomes the resistance of the springs 13^d and forces the piercing punches 19 through the tank wall to make the four rivet holes in said tank wall, as indicated in Fig. 10. On the up stroke of the press, the lower plate 13^b acts as a stripper for the punches 19 and 21.

I claim as my invention:

1. The combination with a punch press, of an attachment therefor having a projection with upper and lower dies thereon and shaped to support a radiator top tank after being drawn from sheet metal, upper and lower punches on opposite sides of said projection and operating on the interposed tank walls to provide a plurality of openings and a depression in one wall and a single opening in the other wall, and means controlled by the movement by the press of the upper punch into and out of engagement with the upper die for effecting the simultaneous movement of the lower punch into and out of engagement with the lower die for operating simultaneously on both walls.

2. The combination with a punch press, of an attachment therefor having a projection with upper and lower dies thereon and shaped to support a radiator top tank after being drawn from sheet metal, and upper and lower punches on opposite sides of the projection and operating on the interposed tank walls to simultaneously make in a single operation the rivet holes, the depression, port hole, and overflow tube opening in one wall of the tank and a single rivet hole for the splash plate in the other wall, and means controlled by the action of the press for effecting the simultaneous movement of said punches into and out of engagement with their respective dies.

3. An attachment for punch presses having a body member with a lateral projection, upper and lower dies supported thereby, a pair of substantially parallel plungers slidably mounted in said body member with one plunger longer than the other and extending out of the body member for operation by a movable element of a punch press, a third plunger slidably mounted in said body member in transverse relation to the first two

plungers and actuated by the longer plunger for moving upward the shorter plunger simultaneously with the downward movement of the longer plunger, and a spring pressed rod connecting the shorter plunger for lowering the shorter plunger in the upward movement of the longer plunger and for resetting the third plunger for the longer plunger.

4. An attachment for a punch press having a body member, upper and lower dies supported thereby, upper and lower punches for said dies, a set of plungers all slidably mounted in and guided by said body member and associated with said punches, said plungers coacting one on the other within said body member in the movement by the press of one punch into engagement with its associated die for effecting the simultaneous movement of the other punch through said plungers into engagement with its associated die, and means for effecting the movement of the last named punch from its die as the press moves the first punch from its die.

5. An attachment for a punch press having a body member, upper and lower dies supported thereby, upper and lower punches for said dies, first and second upright plungers slidably mounted in said body member in substantially parallel, laterally spaced relation and respectively connected with said upper and lower punches and extending downward therefrom, a third plunger slidably mounted in said body member at the lower ends of said first two plungers and arranged transverse thereto, said plungers having coacting cam surfaces at their adjacent ends for moving the second plunger upward in the downward movement by the press of the first plunger, and means for effecting the movement of the second plunger downward in the upward movement of the first plunger and for resetting the third plunger for said first plunger.

6. An attachment for a punch press having a body member, upper and lower dies supported thereby, upper and lower punches for said dies, first and second upright plungers slidably mounted in said body member in substantially parallel, laterally spaced relation and respectively connected with said upper and lower punches and extending downward therefrom, a third plunger slidably mounted in said body member at the lower ends of the first two plungers and arranged transverse thereto, said plungers having coacting cam surfaces at their adjacent ends for moving the second plunger upward in the downward movement by the press of the first plunger, a rod connected with the second plunger and extending downward therefrom, and a spring acting on the rod to normally move the second plunger downward and causing resetting of the third plunger in the upward movement by the press of the first one.

7. An attachment for a punch press having a body member, upper and lower dies support-

ed thereby, upper and lower punches for said dies, first and second upright plungers slidably mounted in said body member in substantially parallel, laterally spaced relation and respectively connected with said upper and lower punches and extending downward therefrom, a third plunger slidably mounted in said body member at the lower ends of the first two plungers and arranged transverse thereto, said plungers having coacting cam surfaces at their adjacent ends for actuating

the second plunger by the first plunger through the third plunger, and a spring pressed rod connected with the second plunger and extending downward therefrom through an elongated slot in the adjacent end of the third plunger.

In testimony that I claim the foregoing as my invention, I affix my signature this 27 day of February, 1925.

GEORGE H. PICKHARD.
